ISAAC L. WESSEL, OF MUSKEGON, MICHIGAN; WILLIAM A. WESSEL ADMINISTRATOR
OF SAID ISAAC L. WESSEL, DECEASED

GRAPPLE FOR HANDLING HOT CASTINGS

Application filed June 13, 1928. Serial No. 285,189.

This invention relates to grapples of the crossed lever type commonly used from a hoist carried by roller and track to lift and transport heavy castings such as cylinder blocks.

The use of the crossed lever type of grapple for lifting hot cylinder blocks from their molds, for example, requires, ordinarily, two men, one at each side of the line of molds, who hold and drop the ends of the grapple over each side of the hot casting. This brings the hands in close proximity with the blocks and despite the use of heavy gloves, frequently causes bad burns.

It is the object of my invention to provide a construction of grapple operable by one man to engage the block and so constructed that the hands of the operative do not need to be brought close to the block.

It is a further object to provide this improved construction in a structural form enabling it to be embodied in the standard form of grapple in common use either as a readily applied attachment for grapples already in use or as a component part of the grapple as originally manufactured.

The invention consists in the combinations, constructions and arrangements herein after claimed and is fully described in the following detailed specification which is to be read in conjunction with the accompanying drawings forming part thereof and in which—

Figure 1 is a perspective detail view of a grapple constructed in accordance with the present invention, the grapple operating arms being shown as dropped from transversely extended operating position;

Figure 2 is a view in end elevation of the crossed angled operating arms, detached;

Figure 3 is a vertical section on line 3—3 of Figure 1, showing the eye-bolt connection between the main grapple and the angled operating arms.

The main grapple is of well known construction comprising the crossed levers 1 and 2 pivoted intermediate of their ends at 3 and having their lower ends provided with the usual confronting grappling teeth 4. The upper ends of the crossed levers 1 and 2, are connected by the usual links 5, and ring 6

from which the usual chain (not shown) extends upwardly to the traveling hoist commonly used in foundry work. As ordinarily used in foundries, the lower ends of the levers 1 and 2 are held by two men at opposite sides of the line of molds and are dropped by them over the side of the hot cylinder block or other casting to be lifted and carried away by the traveling hoist.

Cooperating with and loosely attached to the levers 1 and 2 below their point 3 of pivotal connection are a pair of jaw-expanding angled arms 7 and 8, the lower arms 9 of which terminate in laterally extending handle loops 10. Their upper arms 11 are overlapped above the apices of their angles and pivotally connected at 12, and have their upper ends formed with eyes 13 loosely linked, as by cutting, bending and subsequent welding, with the eyes of eye bolts 14 whose threaded shanks 15 are extended through holes of appropriate size drilled through the grapple levers 1 and 2 below their pivot point 3, and are locked thereon by nuts 16, preferably cottered thereon.

By using angled arms 7 and 8 crossed in reversely angled relation I am enabled to open or expand the lower ends or gripping jaws of the grapple by bringing the handled ends 10 of the pivoted angled arms together. Therefore, one operator grasping with one hand the abutting handled ends 10—10 with the angled arms 7 and 8 lifted and extended transversely away from the main grapple, may manipulate the hoist with his other hand to lower the grapple, positioning the latter (with its jaws held expanded by the angled levers) over the hot casting with the first mentioned hand and holding it so positioned while the hoist is reversely operated to pull up on the expanded jaws 1 and 2 to draw them together and grip the casting therebetween, the angled arms 7 and 8 being now released, leaving both hands free to operate the hoist, if necessary.

The described construction, therefore, permits one operator to perform with safety the entire operation of lowering, positioning, closing and lifting the grapple. The particular construction disclosed while representing

a preferred form of the invention is intended as illustrative thereof and not restrictive.

I claim:—

1. A grapple comprising, pivotally connected levers providing gripping jaws at their lower ends, and a pair of pivotally inter-connected jaw-expanding arms linked at their inner ends to the respective levers of the grapple to extend laterally outward therefrom and having handled outer ends brought into abutting relation by movement of said arms to expand the gripping jaws of the grapple.
2. A grapple comprising crossed pivotally connected levers providing gripping jaws at their lower ends and having hoist connecting linkage at their upper ends for closing said jaws and for raising and lowering the grapple, and a pair of pivotally inter-connected jaw-expanding and positioning arms linked at their inner ends to the respective grapple levers to extend laterally outward therefrom and having handled outer ends, said arms being cross connected to the grapple levers to expand the grapple jaws by closing movement of their handled ends bring said ends together.
3. A grapple comprising crossed pivotally connected levers providing gripping jaws at their lower ends and having hoist connecting linkage at their upper ends for closing said jaws and for raising and lowering the grapple, and a pair of crossed pivotally connected jaw-expanding angle arms loosely linked to the respective levers at their inner ends to extend laterally outward therefrom and having handled outer ends brought together by jaw-expanding movement of said arms.
4. A grapple comprising pivotally connected levers providing gripping jaws at their lower ends and having hoist connecting linkage at their upper ends for closing said jaws and for raising and lowering the grapple, and a pair of angled arms crossed in reversely angled relation beyond the apices of their angles and pivotally interconnected at their point of overlap, with their inner ends loosely linked to the respective levers of the grapple below their pivotal connection to extend laterally outward therefrom and having handled outer ends brought together by jaw-expanding movement of said arms for grasping by one hand of the operator.
5. As an article of manufacture, a jaw expanding attachment for crossed lever type grapples comprising angled arms overlapped and pivotally connected in reversely angled relation beyond the apices of their angles and provided with handled outer ends and loosely linked at their inner ends to grapple engaging members.
